(57) **CLAIM**

The design for the detector, as shown and described.

DESCRIPTION

FIG. 1 is a top, front and left side, perspective view of the detector.

FIG. 2 is a front, right side and bottom perspective view of the detector shown in FIG. 1.

FIG. 3 is a left side, front and bottom perspective view of the detector shown in FIGS. 1 and 2.

FIG. 4 is a top, right side and front perspective view of the detector shown in FIGS. 1-3.

FIG. 5 is a left side, front and bottom perspective view of the detector shown in FIGS. 1-4 with the visor removed.

FIG. 6 is a top and front perspective view of the detector shown in FIGS. 1-5 with the visor removed, as shown in FIG. 5; and,

FIG. 7 is a top, left side and front perspective view of the detector shown in FIGS. 1-6 with the visor removed, as shown in FIGS. 5 and 6.

The back of the lower portion is substantially plain.

The broken lines are not part of the invention.

The rear of the vertical housing of the design is not part of the claimed design.
